a corporation of New Jersey

Application December 30, 1950, Serial No. 203,712

10 Claims. (Cl. 339—102)

This invention relates generally to an electrical apparatus and more particularly to an electrical connector of the type having contact elements with a split terminal portion imbedded in a molded body and a method of molding an electrical connector having such characteristics.

In providing multi-contact electrical connectors, it is frequently desirable to provide a connector of the type having a molded body in which are imbedded a plurality of contact elements. If female contact elements having a split terminal portion and of the type adapted to receivably engage a bayonet-type male contact element are provided, the problem of providing a molded body for the connector structure becomes especially difficult since it is essential that the hollow recesses provided in the contact be free and clear of any of the molded material used in the formation of the connector body.

We have overcome all such difficulties by providing in accordance with the present invention a connector contact member having a split terminal receiving portion surrounded by an enclosure member so that both the contact member and the enclosure member may be integrally imbedded in a molded body. The enclosure member, together with the contact member operates to completely isolate the split terminal-receiving portion of the contact member so that the material used in the formation of the connector body will not be displaced into the hollow recesses thereof.

According to the molding method contemplated by the present invention, the contact members of the connector structure form a part of a sub-assembly which is molded into the connector body. A portion of the subassembly is subsequently removed from the connector body and the connector contact members are integrally imbedded in the connector body.

It is an object of the present invention, therefore, to provide a connector with contact members of the type having a split terminal-receiving portion and a molded body integrally imbedding the contact members, but not interfering with the efficiency of the split terminal-receiving portion thereof.

Another object of the present invention is to provide a method of forming a connector with contact members having a split terminal-receiving portion and a molded body whereby the material used in forming the body will not enter the hollow recesses of the terminal-receiving portion.

A further object of the present invention is to provide improved contact terminal structures for a molded connector body.

A further object of the present invention is to provide a compound contact terminal for a molded connector body.

Many other advantages, features and additional objects of the present invention will become manifest to those versed in the art upon making reference to the detailed description which follows and the accompanying sheets of drawings in which the principles of the present invention are structurally applied by way of preferred embodiment.

On the drawings:

Figure 1 is an end elevational view of the electrical connector constructed in accordance with the principles of the present invention;

Figure 2 is a plan elevational view of a lower mold section with the electrical connector of Figure 1 positioned therein and shown in cross-section, the section being taken on line II—II of Figure 1;

2

Figure 3 is a fragmentary enlarged cross-sectional view taken on line III—III of Figure 2;

Figure 4 is a reduced cross-sectional view with parts shown in elevation and somewhat diagrammatic in part showing details of construction of additional molding components and taken substantially on the plane of line IV—IV of Figure 2;

Figure 5 is a cross-sectional view, fragmentary in part and with parts broken away and parts shown in elevation showing additional details of structure of the electrical connector of the present invention and also showing the method of assembling a sub-assembly of the connector structure with the molding components, the section of the connector member being taken substantially on line V—V of Figure 1;

Figure 6 is an exploded elevational view with parts shown in cross-section of a compound contact member provided in accordance with the present invention;

Figure 7 is a fragmentary cross-sectional view of a compound contact element provided in accordance with the present invention; and

Figure 8 is a fragmentary enlarged cross-sectional view of a single contact member provided in accordance with the principles of the invention.

25 As shown on the drawings:

The electrical connector of the present invention is indicated generally by the reference numeral 10 and includes a molded body 11 which is integrally molded on the end of a cable 12 preferably covered by a sheet of rubber 13 and having a plurality of conductors 14 and 15, respectively, therein, the conductors 14 being connected to single contact members indicated generally by the reference numeral 16 and the conductors 15 being connected to the separated parts of a compound contact member indicated generally by the reference numeral 17.

In producing an electrical connector 10, the end of a cable 12 is first stripped to bare the conductors 14 and 15 and a retainer plate 18 preferably made of an electrically non-conductive material suitably apertured to position a plurality of contact members is employed to align the contact members 15 and 17 in spaced apart relation after which the ends of the conductors 14 are soldered to the contact members 16 and the ends of the conductors 15 are soldered to separate elements of the compound contact member 17.

It will be noted that each of the single contact members 16 is of generally cylindrical configuration and includes a medial annular rib 16a which is positioned proximately adjacent a terminal receiving portion split as at 16b to provide a pair of contact fingers 16c and 16d (Fig. 8). The opposite end of the contact members 16 is provided with a recess in which the end of the conductor 14 may be inserted for a solder connection.

As is particularly shown on Figures 6 and 7, the compound contact member 17 includes opposed cylindrical segments 19 and 20 each having a medial rib 19a and 20a, respectively. One end of each of the segments is provided with a recess 19b or 20b arranged to receive the end of one of the conductors 15 and the opposite ends 19c and 20c form a pair of separated terminal engaging portions.

A block of electrically non-conductive material 21 is inserted between the opposed segments 19 and 20 and a washer 22 also made of electrically non-conductive material is placed in encircling relationship relative to the segments 19 and 20 and the block 21.

After the contact members 16 and 17 have been soldered to the ends of the conductors 14 and 15 an enclosure assembly is assembled around the split terminal portion of each of the contact members.

In reference to the single contact members 16, a tubular sleeve 23 is placed in surrounding relationship to the contact fingers 16c and 16d and into abutting engagement with the annular rib 16a.

In reference to the compound contact member 17, a tubular sleeve 24, which could be made of an electrically non-conductive material or which, in any event, has the internal bore thereof rendered electrically non-conductive, for example, through the provision of an electrically non-conductive lining 25, is spaced in surrounding rela-

tionship to the terminal engaging portions 19c and 20c and into engaging abutment with the washer 22.

A mold plate 26 is provided in accordance with the present invention and has a plurality of locator pins 27 extending from one face thereof, the locator pins 27 corresponding in number and size to the male prongs of a plug adapted to cooperate with the contact members 16 and 17 of the electrical connector 10.

In the particular embodiment of the mold plate shown in Figures 1 and 5, the locator pins 27 are firmly assembled with the mold plate 26 and are spaced in predetermined alignment relative to protruding portions 28 formed on the mold plate 26 to provide a recess 29 in the molded rubber-like body 11 of the electrical connector 10 (Figure 1).

The mold plate 26 is further provided with an opening 30 which extends therethrough and which is adapted to pass a bolt 31 having a threaded end portion engageable with the retainer plate 18, the retainer plate 18 having a suitably threaded aperture 18a formed therein to receive the bolt 31.

It will be noted upon making reference to Figure 5 that the bolt 31 includes a threaded portion 31a which is of reduced diameter so as to provide a shoulder 31b against which the retainer plate 18 may be seated, thereby to predetermine the aligned assembly of the retainer plate 18 with respect to the mold plate 26.

Having the structural features of the mold plate 26 in mind, it will be apparent that the contact members 16 and 17 may be connected to the mold plate 26 to form a sub-assembly by locating a washer of insulating material 35 on each of the locator pins 27 and thereafter positioning the tubes 23 on the single contact elements 16 and the tube 24 on the compound contact member 17 to engage and abut the washers 35 so that the contact members and sleeves may be drawn up in firm assembly with the mold plate 26 by threading the bolt 31 in assembly with the retainer plate 18.

An upper mold section 33 and a lower mold section 34 are provided, each having a recess 33a and 34a, respectively, together forming a molding cavity of a shape complementary to that of the body 11 of the electrical connector 10 and into which molding material may be transferred.

A semi-cylindrical cable-receiving recess is also formed in each of the mold sections 33 and 34 and extends outwardly from the molding cavity to one edge of the mold section so that the cable 12 may have its end positioned within the molding cavity.

Along the length of the semi-cylindrical recess in each of the mold sections 33 and 34 is formed an enlarged recess 33b and 34b which together form a clamp-receiving keyway. A clamp indicated generally by the reference numeral 36 and made up by a pair of similarly constructed half-sections shaped to form a front key portion 36a, a central body portion 36b and a rear key portion 36c is securely fastened to the cable 12 upon tightening a plurality of Allen-head screws 37 situated in the front and rear key portions 36a and 36b and adapted to radially collapse the half-sections of the clamp 36 into firm assembly with the cable 12.

The front key portion 36a of the clamp 36 is firmly locked in place in the keyway recesses 34b and 33b and the rear key portion 36c of the clamp 36 will engagingly abut one side of the mold sections 33 and 34, therefore, the cable 12 will be securely locked to the mold sections 33 and 34 by the clamp 36 during the actual transfer of molding material into the molding cavity so that the cable 12 cannot be displaced under the effects of molding pressure.

The mold plate 26 is also mounted in firm assembly with the upper mold section 33 and the lower mold section 34 through the provision of a mold plate recess 38 formed in the lower mold section 34 and a corresponding mold plate recess formed in the upper mold section 33.

Having positioned the mold plate 26 in the keyway formed by the mold plate recess 38 in the lower mold section 34 and the corresponding recess formed in the upper mold section 33 and having key positioned the clamp 36 between the upper and lower mold sections 33 and 34, the connector body 11 is formed by transferring a supply of molding material from a well 39 formed in the upper mold section 33. A suitably powered ram 40 cooperates with the well 39 and forces the molding material through a plurality of sprues 41 extending between

the well 39 and the molding cavity. The sprues have outlets 41 which in this preferred embodiment, are situated near the back end of the molding cavity so that the molding material may flow toward the mold plate 26 and in and around the conductors 14 and 15, as well as the contacts 16 and 17.

The molding material preferably takes the form of a thermoplastic material, for example, a compounded rubber (either natural or synthetic) or any other electrically non-conductive substance capable of being plasticized and effectively used in a connector structure.

Because of the enclosures formed around the contact fingers 16c and 16d of each of the single contacts 16 and the terminal-engaging portions 19c and 20c of the compound contact member 17 by the tubular sleeves 23 and 24 and the elements cooperating therewith, none of the material used for forming the body 11 will be forced into the locale of the split terminal-receiving portions of the contacts 16 and 17.

After transfer of the molding material has been completed, the mold may be broken and the clamp 36 and the mold plate 26 removed from the connector 10, whereupon the contact members 16 and 17 will be integrally imbedded in the molded body 11, together with the washers 31 and the tubular sleeves 23 and 24.

The finished connector 10 has all of the advantageous features available through the provision of a molded body and split terminal contact members in an integral article of manufacture.

Although we have resorted to detail in the description of the preferred structural embodiment of our inventive principles, it should be understood that we wish to embody within the scope of this invention all such modifications as reasonably and properly come within the scope of our contribution to the art.

We claim as our invention:

1. A connector comprising a contact member having a split terminal-receiving portion, an annular rib extending radially outwardly of said contact member adjacent the split terminal-receiving portion, a rigid insulator sleeve having one end abutting said rib and arranged to surround the split terminal-receiving portion, a washer engaging the other end of said sleeve and operable together with said sleeve to isolate the split terminal-receiving portion, and a molded body integrally imbedding and bonded to the contact member and the sleeve, said washer being imbedded in said body adjacent one edge thereof and forming an opening free of molding material for said split terminal-receiving portion.

2. A connector comprising an elongated contact member having a medial annular rib and a split terminal portion, a rigid insulator sleeve surrounding the split terminal portion and engaging said rib to provide a molding pressure resistant, insulating enclosure around said split terminal portion and a pressure molded body integrally imbedding and bonded to said contact member and said sleeve, whereby said split terminal portion is isolated.

3. A connector comprising a plurality of contact members each having a split terminal-receiving portion on one end, an annular rib extending radially outwardly on each of said contact members adjacent the split terminal-receiving portion, a rigid insulator sleeve engaging each of said ribs and surrounding each of said split terminal-receiving portions, a washer engaging the other end of each of said sleeves, a retainer apertured to receive the other ends of said contact members and to hold same in aligned assembly, said ribs engaging said retainer and a molded body integrally imbedding and bonded to said retainer, said contact members, said sleeves, and said washers.

4. A connector comprising a cable having a plurality of conductors therein, a retainer plate having a plurality of spaced apart apertures, a contact member carried in each of said apertures and being firmly connected to the end of a corresponding conductor in said cable, a split terminal portion formed in each contact member, a rigid insulating enclosure surrounding each split terminal portion, and a molded body integrally imbedding and bonded to said retainer plate together with said conductors, said enclosures and said contact members, said body having an opening and said retainer plate having a threaded aperture in registry therewith cooperable with locking means to hold said retainer plate, said contact members and said enclosures in firm assembly during molding of said body around the end of said cable.

5. A connector comprising a generally cylindrically conformed contact means having a hollow rigid insulator

sleeve with uninterrupted longitudinally extending walls and having a plug-receiving aperture at one end, a longitudinally split socket terminal means extending into said sleeve but terminating short of the apertured end of said tubular portion, and means integrally imbedding and bonded to said contact means including a molded body enclosing all of said sleeve without closing the aperture in the end thereof.

6. A connector comprising a generally cylindrically conformed contact means having an enlarged medial portion and a longitudinally split socket terminal means extending away from one side of said medial portion, a rigid sleeve made of insulating material and having an uninterrupted wall portion sealingly engaging said enlarged portion and surrounding said socket terminal means in concentrically spaced relationship therewith, said sleeve being of greater length than the longitudinal extent of said socket terminal means, conductor wire means connected to said contact means on the other side of said medial portion, and a molded body integrally imbedding and bonded to said conductor wire means, said contact means and said sleeve, said molded body having a plug-receiving aperture in registry with the end of said sleeve and said socket terminal means.

7. A connector as defined in claim 6 wherein said contact means comprises a compound contact terminal having a plurality of segments together forming a generally cylindrical contact member.

8. A connector as defined in claim 7, and a block of electrically non-conductive material between a portion of each of said segments, whereby one end of said contact member comprises separated terminal-engaging portions.

9. A connector as defined in claim 2 wherein said contact member comprises means providing a plurality of segments together forming said contact member, a rib portion medially disposed on each of said segments and together with one another forming said medial annular rib.

10. A connector as defined in claim 9, and a block of electrically non-conductive material between a portion of each of said segments, whereby one end of said contact member comprises separated terminal engaging portions.
